[57] ABSTRACT

Vertically spaced rail members that extend longitudinally of the railway vehicle across and between the car vertical wall posts to prevent transported lading such as boxes, or other types of cartons from contacting the vertical wall posts during vehicle impact resulting in damage to the lading. The rail members provide a smooth car interior and include transversely extending flange portions which strengthen the rail members and the railway car side wall structure by forming a channel shaped section between adjacent wall posts.

FIG.4

RAILWAY CAR INTERIOR WALL STRUCTURE

BACKGROUND OF THE INVENTION

1. Field of the Invention

The field of art to which this invention pertains is railway boxcars and in particular to the interior wall structure of such vehicles.

2. Description of the Prior Art

Prior art car interior wall structures generally comprise a continuous sheet structure extending between the ends of the vehicle and between the floor and the roof structure. Since a prime purpose of the interior wall surface is to prevent lading from abutting or contacting the vertical wall posts which results in damage to the lading, it is apparent that much of a continuous inner wall structure is unnecessary and not used to its fullest extent. Therefore, it is desirable to obtain an interior wall structure which prevents the lading contacting the vertical wall posts and eliminates inconveniences associated with a continuous sheet or an abutting sheet type of wall configuration.

SUMMARY

This invention relates in particular to a freight car having longitudinally spaced vertical wall posts positioned between an outside metallic sheet and the car interior. A purpose of this invention is to solve a problem created when lading within the freight car contacts the vertical wall posts during transport and is prevented from moving longitudinally upon vehicle impact to thereby absorb the impact forces. Another object of the present invention is to provide a rub rail structure extending between the vertical wall posts of the railway vehicle so as to prevent lading from being damaged through contact with the vertical wall post.

It is another object of the present invention to provide a car interior rub rail which is attached to the vertical wall post and includes strengthening flange portions extending transversely which also prevent the exposure of sharp edges to the interior of the car which could damage the lading or injure workers.

BRIEF DESCRIPTION OF THE DRAWINGS

FIG. 1 is a partial perspective drawing with portions cut away of a railway freight vehicle employing the present invention;

FIG. 2 is a top plan sectional view of a portion of the wall structure involved in the present invention;

FIG. 3 is a side elevational view of the interior of the freight vehicle wall structure with a portion cut away;

FIG. 4 is a sectional view taken along line 4-4 of FIG. 3.

DETAILED DESCRIPTION OF INVENTION

With reference now to the drawings and in particular FIGS. 1-4, it is noticed that FIG. 1 illustrates a railway freight car 10 of the usual construction which comprises the usual spaced side sill member 11 and includes a wheeled truck 12 upon which the body of the vehicle is supported. The freight car 10 includes side wall units 13 and longitudinally spaced corrugated end walls 14. A roof structure 15 encloses the top of the vehicle. The floor 16 encloses the bottom of the freight car and supports lading which may be as illustrated by cartons 16a, 16b.

The side wall units 13 include an outer wall sheet or skin 17 which is generally a thin metallic material automatically welded to the vertical wall post 18 which are longitudinally spaced of the freight car 10. The vertical wall posts 18 are of a Z-shaped configuration and include an inner flange 19 exposed to the interior of the freight vehicle and an outer flange 20 fixedly attached to the outer wall skin 17. The inner and outer flange portions 19, 20 respectively are spaced from one another by the central body portion 21. Thus constructed, the railway freight car 10 comprises a generally rectangular shaped closed construction having outer wall portions attached to and supported by vertical wall posts 18. Corner posts 18a are positioned at each of the four corners of the vehicle to facilitate assembly and final attachment of the end walls 14 to the side walls 13.

It is known in the railway art that to protect lading being transported by a railway freight car it is desirable to prevent the lading or the cartons 16a, 16b, as illustrated in FIG. 1, from coming in contact with the vertical wall posts 18 during an impact. Impact loads are effectively absorbed by the lading when the lading is free to move relative to the transporting vehicle. Thus in moving impact loads are absorbed. An undesirable situation is created in railway vehicles of the described configuration when transported material such as the cartons illustrated are not permitted to move longitudinally because of unavoidable contact with the vertical wall post 18. Thus it is desirable to provide a simple and inexpensive and easily assembled method of spacing the transported lading from the vertical wall post to prevent contact between the wall post and the lading resulting in damage to the lading during car impact.

The rub railing members 22 of the present invention are spaced vertically along the inner flange portion 19 of the vertical wall post 18 and extend longitudinally of the railway vehicle between the door openings (not shown) and the end wall 14. The rub rail 22, as illustrated in detail in FIGS. 2, 3, 4, includes a flat enlarged outer body portion 23 which abuts the inner flange 19 of the vertical wall post 18 and is fixedly attached thereto as by a weld or other convenient method of fastening. The upper flange 24 and the lower flange 25 extend outwardly of the vehicle toward the outer wall skin 17 to define a channel shaped section and to thereby lend strength to the rub rail and to the side wall unit and also to conceal the sharp edges 26 from contacting the lading and damaging it. The flange members 24, 25 are so formed as to provide a smooth interior surface having rounded corners.

Thus it is noticed that the rub rail member 22 of the present invention effectively prevents the cargo from contacting the vertical wall posts and being damaged thereby and also provides a thin interior skeletonized wall structure which is strong and yet provides for increased volumetric capacity of the freight car. The inherent rigidity added to the rub rails by the upper and lower flanged portions 24, 25 respectively to increase the torsional and bending strength produces an inherently stiff member which adds structural integrity to the side wall.

The foregoing description and drawings merely explain and illustrate the invention and the invention is not limited thereto, except insofar as the appended

claims are so limited, as those skilled in the art who have the disclosure before them will be able to make modifications and variations therein without departing from the scope of the invention.

What is claimed is:

1. A railway freight carrying vehicle having side walls with outer wall sheathing supported by longitudinally spaced vertical wall posts, cargo rub rail means forming a vehicle interior wall and including:

a plurality of vertically spaced and longitudinally extending rub rail members fixedly attached to said wall posts to form a skeletonized inner wall of said freight vehicle;

each rail member having an enlarged attaching portion overlying said vertical wall posts and having a rigidifying portion positioned between said vertical wall posts and said rigidifying portion having chan-

nel portions extending toward the outer wall sheathing;

said rigidifying portion having a web section extending between the channel portions and generally coplanar with the enlarged attaching portion to thereby provide a continuous smooth vehicle interior wall surface.

2. The invention according to claim 1, and: said vertical wall posts having outer flange means for attachment of the outer wall sheathing and having inner flange means for attachment of the enlarged attaching portion of the rub rail means.

3. The invention according to claim 1, and: said rub rail means being a continuous unitary sheet means having said channel portions integrally formed therein.
